UNITED STATES PATENT OFFICE.

JOHN T. HAWKINS, OF TAUNTON, MASSACHUSETTS.

MACHINE FOR VARNISHING PRINTED SHEETS OF PAPER.

Specification forming part of Letters Patent No. 310,200, dated January 6, 1885.

Application filed October 22, 1884. (No model.)

To all whom it may concern:

Be it known that I, JOHN T. HAWKINS, of Taunton, in the county of Bristol and State of Massachusetts, have invented certain new and useful Improvements in Machines for Varnishing or Glossing Printed Sheets of Paper or Similar Material, which invention is fully set forth and illustrated in the following specification and accompanying drawings.

The object of this invention is to provide, in a machine for varnishing or glossing printed sheets, a simple and efficient method of moving the varnish-depositing roller at proper intervals to and from the cylinder carrying the sheet, while maintaining said roller at a fixed distance from the varnish-fountain roller. It is also its object to provide an easy means of adjusting the contact of the varnish-depositing roller with both the varnish-fountain roller and the sheet-carrying cylinder; and, also, to provide a simple means of operating the hinged feed-board and front sheet-guides, and to provide for partially drying the sheets before delivering them upon endless tapes by means of a rotating fan, which shall at the same time by its blast press the sheets against the sheet-cylinder to prevent their falling back when the grippers open to release them. A further object is to arrange the varnish-fountain so as to be readily lowered away from its roller for the purpose of cleansing.

The invention consists of the parts and combinations of parts as hereinafter described and claimed.

In said drawings, Figure 1 is a side elevation of the machine, the delivery-tapes and feed-board being broken out to save space on the drawing. Fig. 2 is an end elevation viewed from the left-hand side of Fig. 1. Fig. 3 illustrates in two views the eccentric bushes in which the varnish-depositing roller is journaled. Fig. 4 illustrates in two views the eccentric-studs carried in the long arm of the bell-crank lever, which carries the varnish-depositing roller. Fig. 5 illustrates the arrangement for operating the feed-board and front sheet-guides.

In said figures, the letter A indicates the two main side frames, in which is journaled a cylinder, A', provided with the usual grippers and sheet-lifter fingers. (The latter two not seen in the drawings.)

A² indicates a slotted tumbler-cam, secured to the gripper-shaft and operated in the usual way by the opening and closing studs A³ A⁴, 55 secured to one of the frames A.

B indicates the feed-board hinged at B'.

To a shaft, B², journaled in the frames A, is secured an arm, B³, carrying on its free end a roller, B⁴. The roller B⁴ engages a suitably formed groove in the head of the cylinder A'. 60

Secured to shaft B² are two more arms, B⁵, upon which the front end of the feed-board B rests. Secured, also, to shaft B² are two or more guides, B⁶, against which the 65 sheets are fed when they project above the feed-board B. The groove in the head of cylinder A', which engages the roller B⁴, is of such form as to lift the front end of the feed-board B just as the grippers are closed upon 70 the sheet previously fed to the guides B⁶, and to lower it again when the whole of the sheet shall have passed off it. The arms B⁵ and guides B⁶ extending in opposite directions from the rock shaft B², the guides fall simultaneously with the lifting of the feed-board, and 75 vice versa.

C indicates the varnish-fountain, and C' the fountain-roller journaled in the frames A. Journaled also upon the ends of the shaft of 80 the fountain-roller C', outside of the frames A, are two bell-crank levers, C². Carried in the short arms of the levers C² are eccentric bushes C³, secured adjustably in any position by the nuts C⁴ by means of pin-wrenches, as shown. 85 Journaled in the eccentric bushes C³ is the varnish-depositing roller C⁵. Carried in the ends of the long arms of levers C² are eccentric studs C⁶, carrying rollers C⁷, and adjustably secured into position by the nuts C⁸. On 90 the axle of cylinder A', at either end, are carried the two-leaved cams D, one leaf of each of which is secured to the cylinder-axis, and the other adjustably secured to it by means of the curved slots D' and bolts D² for the purpose of lengthening or shortening the higher surface of said cams for longer or shorter sheets. 95

Attached at one end of the levers C², and at the other ends to pins in the frames A, are two spiral springs, D³, acting to keep the rollers 100 C⁷ in contact with the cams D at all times. By the rotation of the eccentric studs C⁶ in the levers C², the nearest approach of the roller C⁵ to the cylinder A' may be accurately adjusted

and fixed, thus regulating the pressure of the depositing-roller C⁵ upon the paper. By the rotation of the eccentric bushes C³ in the levers C², the approach of the depositing-roller C⁵ to the fountain-roller C' may be accurately adjusted and fixed, thus adjusting the film of varnish taken by the depositing-roller from the fountain-roller. Secured to the cylinder A' is a gear-wheel, E. Secured to the axis of the depositing-roller C⁵ and meshing with the gear E is a gear-wheel, E'. Secured to the axis of the fountain-roller C' and meshing with the gear-wheel E' to escape gear-wheel E is a gear-wheel, E''. Upon the shaft E' is secured a pinion, E'', meshing with the gear-wheel E; and upon the same shaft, E', are secured suitable pulleys, E³, and a fly-wheel, E⁴, through the former of which, by means of suitable belts, the whole is actuated, or by a handle placed in the latter it may be driven by hand-power. The rise and fall of the cams D is not sufficient to allow the gear E' to pass out of mesh with the gear E, but only sufficient to remove the varnish-depositing roller C⁵ far enough from the cylinder A' to prevent the deposition of varnish upon those parts of the cylinder A' not covered by the sheet. The depositing-roller C⁵ is, for sheets narrower than the length of cylinder A', made of the proper length at its greatest diameter to suit the width of the sheet, this length being varied for different widths of sheet. On a rod, F, secured at the ends to the frames A, are secured a series of stripper-fingers, F', for stripping the sheet from the cylinder A' and leading it to a series of tapes, F². On a shaft, F³, journaled in frames A, are secured a series of tape-pulleys (not shown in the drawings) carrying on one end the endless tapes F². Rising from and secured to the back end of feed-board B are two standards, F⁴, in which is journaled a shaft, F⁵, to which is secured a series of tape-pulleys, F⁶, which carry the other end of the endless tapes F². Upon the stud F⁷, secured to one of the frames A, runs an idler-gear, F⁸, meshing with the gear E and with a gear, F⁹, secured to the shaft F³, giving the proper motion to tapes F². Journaled in the frames A is a shaft, G, carrying a series of fans, G'. Secured to one end of shaft G is a pulley, G². Upon the shaft F³ is secured a pulley, G³, and pulleys G² G³ are connected by a belt, G⁴. The fountain C is secured to two brackets, I, one end of each of which is jointed at I' to the cross-stay I². Screwed into the frames A are two milled-headed pins, I³. The points of these pins are tapered and enter corresponding taper-holes in the ends of the fountain, as shown, supporting it in place. Upon the removal or partial withdrawal of pins I³ the fountain C may be lowered, swinging on the pivots I' into position for cleansing, at the same time leaving the roller C' accessible for the same purpose.

Having thus fully described my said improvements, as of my invention, I claim—

1. In a machine for varnishing, glossing, or sizing paper or other similar material, a depositing-roller, as C⁵, adjustably journaled in arms, as C², swinging upon the axis of a fountain-roller, as C', whereby said depositing-roller is held at an adjustably-fixed distance from said fountain-roller, and also adapted to be moved to and from a sheet-cylinder, as A', substantially as and for the purposes set forth. 73
2. In a machine for varnishing, glossing, or sizing paper or other similar material, the combination of gearing for actuating the depositing and fountain rollers, consisting of a gear-wheel, as E, secured to the sheet-cylinder, meshing with an intermediate gear, as E', secured to the depositing-roller, and this latter meshing with a third gear, as E'', secured to the fountain-roller, substantially as and for the purposes set forth. 75
3. In a machine for varnishing, glossing, or sizing paper or other similar material, the combination, with a depositing-roller, as C⁵, adjustably journaled in levers, as C², swinging upon the axis of a fountain-roller, as C', of adjustable cams, as D, and springs, as D³, for automatically swinging the said levers upon the axis of said fountain-roller as a fulcrum, and thus moving the said depositing-roller to and from a sheet-cylinder, as A', substantially as and for the purposes set forth. 80 90
4. In a machine for varnishing, glossing, or sizing paper or other similar material, in combination with a sheet-cylinder, as A', a rotary fan, as G', whereby the double purpose of pressing the sheet against the said sheet-cylinder and partially drying the varnish or other deposited material by the blast of said fan is accomplished, substantially as and for the purposes set forth. 95
5. In a machine for varnishing, glossing, or sizing paper or other similar material, or other machine to which sheets of paper are to be under-fed to a sheet-cylinder, as A', the combination of front guides and hinged feed-board, consisting of a rock-shaft, as B², levers for lifting the feed-board, as B³, and front guides, as B⁴, secured to said rock-shaft and extending in the opposite direction from said levers, and an actuating-lever, as B⁵, the latter operated to oscillate said rock-shaft, substantially as described, by any suitable connection to the machine, substantially as and for the purposes set forth. 105 110 115
6. In a machine for varnishing, glossing, or sizing paper or other similar material, a swinging varnish-fountain, as C, fulcrumed to any suitable part of the machine, as to the cross-stay I², so as to swing clear of a varnish-roller, as C', and held in position by suitable pins or screws, as I³, substantially as and for the purposes set forth. 120 125
